[57] CLAIM

The ornamental design for a pressurized dispensing container, substantially as shown and described.

DESCRIPTION

FIG. 1 is a top perspective view of a pressurized dispensing container showing our new design;

FIG. 2 is a perspective view from above and to an opposite side from the side shown in FIG. 1;

FIG. 3 is a front elevational view thereof;

FIG. 4 is a side elevational view;

FIG. 5 is a back elevational view thereof;

FIG. 6 is a top view thereof; and

FIG. 7 is a bottom view thereof.
